UNITED STATES PATENT OFFICE.

T. E. WEED, OF WILLIAMSBURG, NEW YORK.

GRAIN-DRIER.

Specification of Letters Patent No. 8,764, dated February 24, 1852.

To all whom it may concern:

Be it known that I, T. E. WEED, of Williamsburg, county of Kings, State of New York, have invented a new and useful Machine for Drying Malt Grain, &c., the same being treated by steam and a current of hot air also applied for carrying out the operation; and I do hereby declare that the following is a full and exact description of the 10 construction and operation of the same.

The nature of my invention consists in the combination of a series of circular steam chambers with the same number of circular pans arranged alternately one above the 15 other for creating a great amount of surface by that means making it practical for drying malt which has not heretofore been done with any success with machines on account of not having sufficient surface to hold any 20 quantity at a time but in this machine the difficulty is obviated for the chambers and pans can be made any required circumference and also any number arranged one 25 above the other. A current of air is also applied in such a manner that it is all the time blowing over the different surfaces and also passes through the grain a number of times in its passage through the machine and carries off all the vapor or steam that 30 rises which is very essential in drying malt as a very great amount of evaporation takes place.

In most of machines for drying grain, &c., a difficulty is experienced by the grain getting injured from the vapor that rises from 35 some portion of it and coming in contact with another portion which steams or scalds and consequently must injure the quality of the article materially but in this case the 40 vapor is all driven away as fast as it rises by a current of air in such a manner that it produces an entirely different effect, and even if the current of air is not applied the grain resting on one surface can in no way 45 injure that which is above it, as each surface is solid material and the vapor cannot get through but must pass off around the outer edge from its own gravitation.

For a full description of the different 50 parts and the working and operation of the same, I refer to the accompanying drawings by letters. The same letters refer to like parts.

Figure 1 is a perspective view of the machine, Fig. 2 is a vertical section. Fig. 3 is 55 a plan view of the chamber with the pan

underneath, and scrapers dotted. Fig. 4 is a plan view of the pan with the opening in the center.

A A are circular steam chambers composed of two plates of boiler iron or other material suitably secured together around the outer edge steam tight leaving about three inches hollow space between for the steam to circulate; the top plate is a plane flat surface the bottom plate decends to the center sufficient to allow the condensed water to pass down the shaft B B and escape from the pipe T.

B B is a hollow shaft extending through the center in sections and supports each of the chambers A A in their positions and through which the steam passes into them for heating the machine. The chambers are made sufficiently strong to stand the same 75 pressure of steam, as the boiler consequently any degree of heat can be regulated that is required.

C C are circular pans made of sheet iron or other materials suitably supported by 80 arms D which are secured to the main shaft B B. The pans are made larger in circumference than the steam chambers, and catch the grain as it falls from them which is then conducted to the center and falls through 85 the opening in the pan onto the next steam shaft.

F F is a frame work that revolves around the top part resting on the head of the main shaft which forms a kind of pivot on which 90 it turns. The bottom turns on a ring made on the shaft which keeps the frame work steady and prevents its wabbling or wavering in any manner.

g g are scrapers secured to the arms H 95 H which are made fast to the frame work F F and revolve around with the same. The scrapers g g are set at an angle with the grain for either carrying it out from or into the center. Those on the steam chambers operate as the grain falls on to carry it from the center in a circle to the outer edge and the pans being larger in circumference catch it as it falls, and the scrapers on the pans being set at a reverse angle with those on the steam chambers carry it back to the center and falls through the opening onto the next steam chamber which is then carried out in the same manner, and so on 105 throughout any number of chambers, and 110 pans that may be arranged.

I I, are small chambers that extend

around the center shaft in each of the spaces between the chambers and pans.

J J are slots or openings in the chambers and extend all around them.

5 K is a pipe that extends up through the machine with an opening into each of the chambers I I a current of hot air is forced to the pipe and passes into each of the chambers from which a thin blade escapes 10 through the slots or openings J J and passes off in a circle from the center, at a right angle or nearly so with the main shaft. The current of air as it passes off is all the time blowing over a new surface that is stirred up 15 by the scrapers and also passes through the grain as it is loosened up falling from the chambers onto the pans and also falling from the pans onto the chambers which carries off all the vapor that rises.

20 L is an iron bar that supports the weight of the machine.

M, is a cross secured to the floor above and the rod, N, which is secured to the main shaft passes into it to hold the machine in 25 its position keeping it firm and secure in its place.

O is a pulley secured to the frame work for turning the same.

P is a feeder which conveys the grain onto 30 the machine by passing it onto the top steam chamber close around the main shaft and operates by a hopper the same as a mill for grinding.

Q Q, are guards secured to the frame

work F F, and move around with the same 35 to keep the grain from falling over in passing through the machine. The hollow is represented in the shaft in Fig. 2, through which the steam passes into the chambers. The scrapers g g are secured to the arms 40 H H by a square head fitting into a square socket or hole in the arms and each scraper is fitted loosely to rise up and down to suit any unevenness in the surface, as they revolve around. The pipe for conveying the 45 steam from the boiler to the machine connects at R.

1. I claim the center hollow shaft B B for the double purpose first for forming the support in the center for the steam chambers, and pans, as described, and second for forming a passage for the steam to pass into each of the chambers for heating the machine.

2. I claim, substantially as described, the 55 arrangement of the air chambers I I between the steam chambers and pans with openings in them for a thin blade of air to escape in a circle from the center at a right angle or nearly so with the main shaft B B 60 and the pipe extending through the machine as shown for supplying the chambers with air operating substantially in the manner and for the purpose as herein set forth.

T. E. WEED. [L.S.]
